CLAIM

The ornamental design for a handset telephone, substantially as shown and described.

DESCRIPTION

FIG. 1 is a substantially front view of the underneath of a handset telephone showing my new design;

FIG. 2 is a right side elevational view thereof, the left side elevational view being essentially a mirror image of this view;

FIG. 3 is a rear elevation view thereof;

FIG. 4 is a top plan view thereof;

FIG. 5 is a bottom plan view thereof; and

FIG. 6 is a perspective view showing the front, right side and bottom surfaces thereof.

FIG. 1

FIG. 2

FIG. 4

FIG. 5

FIG. 3

FIG. 6
